Specification for Design.

Patented Feb. 22, 1910.

Application filed December 21, 1909. Serial No. 534,398. Term of patent 14 years.

To all whom it may concern:

Be it known that I, CLAYTON F. WETMORE, a citizen of the United States, residing at Jersey City, in the county of Hudson and State of New Jersey, have invented a new, original, and ornamental Design for Name-Blocks or Saddles for Caskets, Coffins, or Similar Articles, of which the following is a specification, reference being had to the accompanying drawing, forming a part thereof, in which—

Figure 1 is a plan view of a name block

showing my design. Fig. 2 is an end elevation thereof, and Fig. 3 is a front elevation thereof.

I claim:

The ornamental design for a name block or saddle for a casket, coffin or similar article as shown.
